UNITED STATES PATENT OFFICE.

FRANCIS B. MATTHEWS, OF PHILADELPHIA, PENNSYLVANIA.

FEED-WATER HEATER.

SPECIFICATION forming part of Letters Patent No. 695,320, dated March 11, 1902.

Application filed September 23, 1901. Serial No. 76,211. (No model.)

To all whom it may concern:

Be it known that I, FRANCIS B. MATTHEWS, a citizen of the United States, residing in Philadelphia, Pennsylvania, have invented 55
5 certain Improvements in Feed-Water Heaters, of which the following is a specification.
My invention relates to certain improvements in feed-water heaters, and has for its object the provision of a device which shall 10
10 utilize a given quantity of steam in heating water more efficiently than has hitherto been possible in any apparatus of this type. This object I attain as hereinafter set forth, reference being had to the accompanying drawings, in which—

Figure 1 is a vertical sectional view of my improved feed-water heater. Fig. 2 is a plan view of the interior of my improved heater as seen when the cover with the regulating-valve 20 and perforated screen are removed; and Fig. 3 is a horizontal sectional view on the line 3 3, Fig. 1.

In the above drawings, A is a cylindrical casing having a flanged cover A', through 25 which there is an opening a. There is also an opening a' in the side of the main heater-casing A, through which projects an L-shaped pipe B, the outer end of this pipe being flanged and bolted to the casing, so as to support 30 said pipe rigidly. There is a partition a², having an opening through its central part, extending across the casing A, and this is inclined downwardly toward said opening. The pipe B extends through this opening, its 35 inner end pointing upward and entering the center of the top of a conical shell C. This shell is made in two sections, one of which, c, has the shape of a truncated cone and is provided around the edges of its top with lugs 40 c', which carry a conical deflector-section c². The cones forming these two sections are preferably similar, and the lower edge of the section c² preferably overlaps the upper edge of the section c', as shown in Fig. 1.

45 As illustrated in Fig. 2, the section c is provided with lugs c³ on its lower edge, and there are projections c³ from the sides of the main casing A, placed to correspond with the lugs c³, to which they are bolted. A portion of the 50 lower edge of the external surface of the conical section c² is recessed to accommodate a perforated conical sheet D, which extends in

continuation of the conical surface of said section c² until it has become of the same diameter across its base as the interior of the casing A.

Bolted to the top A' of the heater A is a valve-casing E, having an inlet e and an outlet e'. In the latter of these is a cylindrical tube e², flanged or bell-shaped at its lower end 60 and having a spider e³ at its upper end, to which is attached a valve-rod e⁴. The cover e⁵ of the valve-casing is provided with the usual stuffing-box e⁶ and has in its lower part a threaded bushing, through which passes a 65 threaded section e⁷ of the valve-rod.

By the revolution of the hand-wheel e⁸ the rod e⁴ is moved vertically, thereby varying the distance of the cylindrical section e² from the cone-section c².

I preferably construct the inside surface of the bell-shaped end of the tubular piece e² parallel with the outside conical surface of the deflecting-section c², so that when the said tubular section is forced against the conical section the passage of any liquid from within the tubular section or through the valve is impossible. It will be noted that the outside surface of the tubular valve e² is finished, and there is a sleeve e⁹ provided where 70 it passes through the valve-casing E.

In operation the pipe B is connected to a source of steam-supply, usually the exhaust from an engine, and the steam is delivered from said pipe against the under side of the 85 conical deflector c². From here it passes downwardly between the outside surface of the conical section c and the inside surface of the perforated section D, passing through the latter into the upper part of the heater-casing A. In the meantime the feed-water to be heated is supplied from a suitable source through the inlet e of the valve-casing E and passes down through the interior of the tubular valve e². If now this is slightly 90 raised, the water flows in a thin film between its bell-shaped lower edge and the upper surface of the deflecting-section c² and spreads over the outside of the section D, meeting relatively thin films of steam both before and 95 after it goes through the perforations. The result of such combination is that the steam and water become thoroughly and intimately mixed, the steam being condensed and its 100

heat imparted to the feed-water in a most efficient manner. The feed-water then passes on to the partition a^2 and flowing through the opening therein drops to the lower part of the heater-casing, where it is drawn off for use as required.

It will be seen that by varying the height of the tubular valve e^2 above the surface of the section c^2 the thickness of the film of water escaping over the conical surface of said section or deflector and the section D may be varied to suit the volume of steam entering through the pipe B, it thus being possible to regulate the thickness of this film, and hence the quantity of water, so that the best results are obtained from the steam supplied.

I claim as my invention—

1. In a feed-water heater, the combination of a casing having an inlet and an outlet for water, a pipe extending into the casing connected to a source of steam-supply, a conical shell surrounding the end of said pipe, a second conical shell over the end of the pipe carried by the first shell and adapted to receive the film of water from the inlet, and a removable screen placed so as to form a continuous surface with the upper surface of the second shell, substantially as described.

2. In a feed-water heater, the combination of a main casing, two conical shells supported within the same adjacent to one another, having a space between them, a steam-pipe connected to the said space between the shells, an opening in the main casing for the admission of water and mechanism in said opening placed to separate water in a film over the surface of one of the shells and means for varying at will the thickness of said film, substantially as described.

3. The combination in a feed-water heater of a main casing, two conical shells supported within the same adjacent to each other, having a space between them, a steam-pipe connected to the space between said shells, a water-inlet to the main casing, a valve connected thereto, and mechanism connected to the valve for spreading the water in a film over the surface of one of the shells and for varying at will the thickness of said film, substantially as described.

4. The combination in a feed-water heater of a main casing, two conical shells supported within the same adjacent to each other, having a space between them, a steam-pipe connected to the space between said shells, a water-inlet to the main casing over the apex of one of said shells, a valve-casing connected to said inlet having mechanism constructed to engage with the said shell whereby the thickness of the film of water flowing over the surface of the conical shell can be regulated, substantially as described.

5. The combination in a feed-water heater of a main casing, two conical shells supported within the same adjacent to each other, having a space between them, a steam-pipe connected to the space between said shells, a water-inlet to the main casing over the apex of the outer one of said conical shells, a valve-casing connected to the opening having a movable tubular piece constructed to engage the outer surface of said conical shell, with means for operating said piece whereby the flow of water into the casing and the thickness of the film thereof over the outer shell may be varied, substantially as described.

6. The combination in a feed-water heater of a main casing, two conical shells supported within the same adjacent to each other, having a space between them, a steam-pipe connected to the space between said shells, a water-inlet to the main casing over the apex of the outer end of said conical shells, a valve-casing connected to the opening having a movable tubular piece provided with flared edges, constructed to engage the outer surface of said conical shell, with means for moving said piece in the line of the axis of the conical shell whereby the flow of water into the casing and therefore the thickness of the film thereof over the outer shell may be varied, substantially as described.

In testimony whereof I have signed my name to this specification in the presence of two subscribing witnesses.

FRANCIS B. MATTHEWS.
